(57) **CLAIM**

The ornamental design for a dispensing device, as shown and described.

DESCRIPTION

FIG. 1 is a perspective view of the dispensing device showing my new design;

FIG. 2 is a top view thereof;

FIG. 3 is a side view thereof;

FIG. 4 is a bottom view thereof; and,

FIG. 5 is a cross-sectional view thereof.

Broken lines are included for the purpose of illustrating environmental structure and form no part of the currently claimed design.
